FUEL COMPOSITIONS

William A. Barr, Brookside, Newark, and James L. Hall, Mount Cuba, Del., assignors to Atlas Chemical Industries, Inc., a corporation of Delaware
No Drawing. Filed Sept. 8, 1958, Ser. No. 759,429
19 Claims. (Cl. 44—63)

This invention relates to liquid hydrocarbon fuel compositions to which anti-static properties have been imparted and to methods of producing the same. Particularly it relates to liquid hydrocarbon fuels which have had their electrical characteristics changed by the addition of acylation products of hydroxy amines derived from hexoses.

Modern engines of the internal combustion type, such as are used in automotive vehicles and propeller driven aircraft, and jet engines, such as are used in military aircraft, make use of a wide variety of liquid hydrocarbon fuels. Many of these fuels have been found to present a serious safety hazard because of their property of forming an explosive equilibrium mixture with air at temperatures encountered under normal storage and handling conditions. Handling these fuels has, in the past, presented a considerable danger because such explosive mixtures may be readily ignited by discharges of static electricity which has been accumulated in the fuel in the course of pumping and transfer operations.

Not all fuels have volatility characteristics which ordinarily permit formation of explosive equilibrium mixtures at normal temperatures. Some fuels have such high volatility that they may not be expected to form such an explosive equilibrium mixture, except at temperatures below those normally encountered, because the vapor mixtures they form in equilibrium with air are too rich to be exploded. On the other hand, other fuels have such low volatility that, except under temperature conditions higher than those normally encountered, they may ordinarily not be expected to produce vapor mixtures which are rich enough to explode.

It should be appreciated that the above discussion is confined to equilibrium conditions. Fuels which do not normally form equilibrium explosive mixtures with air at normal temperatures may form explosive mixtures when compressed or when present with air in the form of a foam or froth. Thus, although automotive fuels do not form explosive equilibrium mixtures above 10° F., it is possible to obtain such mixtures in refinery operations at higher temperatures. For instance, when a tankful of automotive gasoline is blended by "rolling" with air (i.e. air is sparged into the tank as a source of agitation) an explosive mixture can be artificially created.

In general, the fuels with which the present invention will find its principal applicability are those having such volatility characteristics that, within a temperature range between about -20° F. and about 210° F., explosive equilibrium mixtures form in air and more particularly those which form such mixtures between about -20° F. and about 100° F.

Reid vapor pressure, which is measured at 100° F., is one common measure of volatility characteristics. Fuels suitable for use in this invention will be found included within the range of Reid vapor pressures of from about 0.1 to about 15 pounds per square inch.

One of the fuels with which the invention is particularly applicable is JP-4 jet fuel, which is completely described in military specification MIL-F-5624 C. JP-4 fuel which is a low vapor pressure, wide-cut, gasoline type hydrocarbon, forms an equilibrium explosive mixture with air between about 10° F. and about 90° F. and has a Reid vapor pressure of from 2 to 3 pounds. Another

fuel with which the invention may be employed is JP-3 jet fuel, which forms such mixtures at about 45° F. and below, and has a Reid vapor pressure between 5 and 7 pounds per square inch. The invention is also applicable to fuels which are used in internal combustion engines, as, for example, high test aviation gasoline which forms explosive mixtures at about 30° F. and below, and has a Reid vapor pressure between 5.5 and 7 pounds per square inch. It is also useful with kerosene and with ordinary automotive gasoline, which latter forms such explosive equilibrium mixtures to about 10° F. and below and has a Reid vapor pressure between 10 and 15 pounds per square inch. All of these fuels may be successfully treated in the manner described below and, when so treated, are within the scope of this invention.

When dealing with fuels, such as those discussed above, it has been found that an explosion can be triggered by the spark from a charge of static electricity such as can be built up in the fuel body in the course of pumping and filling operations. WADC Technical Report 55-266 of November 1954, entitled, "Frictional Electrification Effects in Fuel Flow" by Dr. F. M. Ernsberger of the Southwest Research Institute (catalogued by ASTIA as AD No. 90288) is a detailed study of the theoretical aspects of this problem. In order to minimize such dangers, many precautions are now taken such as elaborate grounding systems and the use of oversize pipe lines to minimize friction and consequent static build-up.

It has been empirically determined that there is a relationship between the electrical resistivity of liquid hydrocarbon fuels and their ability to build up a charge of static electricity such as is necessary to trigger an explosion. Fuels which have an electrical resistivity of less than about 1×10^{11} ohm-centimeters cannot build up such a charge since the static charge created in such fuels is able, by virtue of the low resistivity thereof, to ground itself as fast as it builds up.

An object of this invention is, accordingly, the provision of liquid hydrocarbon fuel in which static electricity build-up during storage or handling is inhibited so as to minimize the possibility of accidental ignition.

An additional object of this invention is the provision of a fuel composition which is rendered highly conductive by the use of small amounts of selected additives, which additives do not interfere with the combustion characteristics of said fuel.

The above objects of this invention, as well as additional objects, will be apparent to those skilled in the art from a consideration of the following description and examples.

Briefly stated, it has been found that the fuels of the present invention have lower electrical resistivity (i.e. greater conductivity) and are inhibited against the build-up of static electricity preferably by the addition of a small amount of compounds which are acylation derivatives of hydroxy amines derived from hexoses such as glucamine or N-alkyl glucamines. Other hydroxy amines derived from hexoses, which are suitable for subsequent acylation to form the additives of the invention, include amines derived from fructose, glucose, galactose, sorbose and like hexoses; mixtures of glucamines and fructamines (which can be prepared, as is known in the art, by reductive amination of invert sugar—such mixtures being referred to henceforth herein as invertamine), condensation products of the above amines with up to six mols of alkylene oxides (such as ethylene oxide, propylene oxide or mixtures thereof) per mol of amine; and mixtures of any of the above products. All of the above representative materials are intended to be encompassed by the term "hydroxy amines derived from hexoses" as used henceforth herein. Specific examples of such amines include N-methyl glucamine, N,N-dimethyl glucamine, N-ethyl

glucamine, N-methyl fructamine, galactamine and N-butyl fructamine.

The amount of the preferred additives of the invention desirable for anti-static protection is that which is sufficient to reduce the electrical resistivity of the fuel to a value below about 1×10^{11} ohm-centimeters. Usually an amount less than 2 wt. percent will suffice and amounts between .005% and 1.0% by weight are preferred.

The additives employed in this invention are, as stated above, acylation products of hydroxy amines derived from hexoses and include acylation derivatives of glucamine and the N-alkyl glucamines. Details of the preparation of the N-alkyl glucamines may be found in an article by P. Karrer and E. Herkenrath, *Helv. Chim. Acta*, vol. 20, pages 83-86 (1937), and also in an article by Mitts and Hixon, *Jl., Am. Chem. Soc.*, vol. 66, pages 483-486 (1944). Preparations of methyl, ethyl, propyl, n-butyl, isobutyl, pentyl, hexyl and cyclohexyl glucamines are disclosed in these articles.

From these basic materials two types of acylation products which are useful as additives can be prepared. The first of these are amides and amide-esters of hexyl amines, which amines contain at least one amino hydrogen atom capable of amidation. Such hexyl amines include "anhydro" hexyl amines. The prefix "anhydro," as used in this connection, indicates that H_2O has been split out from among hydroxyl groupings to form an inner ether. Other suitable hexyl amines include "cyclized" hexyl amines which contain one amino hydrogen atom. "Cyclized," as used henceforth in this connection, indicates a hexyl amine residue wherein an amino hydrogen and a hydroxyl group have been split off from the molecule in the form of water. "Cyclized" hexyl amines of the type suitable for forming acylation products of this first type (i.e. amides and amide-esters) may also be characterized as heterocyclic secondary amines.

Representative acylation products of the first type include amides and amide esters of: glucamine, "cyclized" glucamine, "anhydro" glucamine, fructamine, "cyclized" fructamine, "anhydro" fructamine, galactamine, "cyclized" galactamine, "anhydro" galactamine, invertamine, "cyclized" invertamine, "anhydro" invertamine, N-alkyl glucamines (wherein the alkyl group contains from 1 to 6 carbon atoms), N-alkyl "anhydro" glucamine (wherein the alkyl group contains from 1 to 6 carbon atoms), N-hydroxyethyl glucamine, N-hydroxyethyl "anhydro" glucamine, and similar compounds all of which contain at least one amino hydrogen before acylation and which, accordingly, form either amides or amide-esters.

Products of the second type may be broadly characterized as esters of tertiary hexyl amines. Representative amines suitable for forming such esters include N,N-dialkyl glucamines (wherein each alkyl group contains from 1 to 6 carbon atoms); N-alkyl, N-hydroxy alkyl glucamines, "cyclized" N-alkyl glucamines, N,N-dialkyl anhydro glucamines (wherein each alkyl group contains from 1 to 6 carbon atoms per molecule), N,N-dihydroxy ethyl glucamine, and analogous compounds derived from other hexyl amines provided always that the product which is acylated is a tertiary amine.

Acylation products of the first type may be formed by heating one mol of the aforementioned amines with one mol of fatty acid at temperatures less than about 175° C. until an amide is formed and one mol of water splits out of the reaction mass. If the reaction is carried out at a temperature of 175° C. or higher, it may be continued beyond the point where only one mol of water splits out. Such further reaction will produce anhydridization or cyclization of the polyol constituent and will result in the production of further quantities of water. Preferred products for use in accordance with the present invention are anhydroamides produced when the reaction is conducted at these higher temperatures for a length of time sufficient to split out two mols of water per mol of fatty acid. Reaction with additional fatty acid will result in the production of amide-esters.

The production of suitable compounds is disclosed in Patent No. 1,985,424 of December 25, 1934, and Patent No. 2,703,798 of March 8, 1955.

Examples of the preparation of some typical amide products of the first type which are suitable for use as additives in hydrocarbon fuel follow:

Example I-A

1,410 grams of oleic acid were added to 990 grams of N-methyl glucamine. To reduce foaming 82.5 grams of the product of a previous batch were added to the reaction mixture. The mixture was heated for 1½ hours at temperatures up to 195° C., during which time 157 cc. of water were evolved and collected from the reaction mass. The resulting product, an oleic amide of anhydro methyl glucamine, had an acid number of 6.2, a saponification number of 29 and a hydroxyl number of 400.

Example I-B

286 grams of stearic acid were added to 200 grams of N-methyl glucamine. The reactants were heated to 180° C. and held between 180° and 185° C. for three hours. During that time 34.5 ml. of water were evolved and collected from the reaction mass. The resulting product, a stearic amide of anhydro methyl glucamine, had an acid number of 3.7, a saponification number of 27.7 and a hydroxyl number of 411.

Example I-C

70 g. of crystalline N-methyl invertamine was reacted with 201 g. oleic acid at 185-234° C. for 3½ hours during which time 21 cc. of aqueous distillate was collected. The product was a viscous dark liquid, acid No. 5.8, sap. No. 96.1, OH No. 144, and 1.95% N. The product is an ester-amide of anhydro N-methyl invertamine.

Example I-D

74 g. of N-methyl invertamine was reacted with 76 g. lauric acid at 171-192° C. for three hours during which time 13.5 cc. of aqueous distillate was collected. The product was a brown pasty water soluble material, acid No. 10, sap. No. 31. The product is a cyclized anhydroamide.

Aliphatic monocarboxylic acids which may be used for the amidation are those having from 12 to 26 carbon atoms per molecule and include among others oleic, erucic, stearic, lauric, tridecanoic, myristic, pentadecanoic, palmitic, margaric, non-adecanoic, arachidic, behenic, cerotic, palmitoleic, elaidic, linoleic, linolenic, aliphatic acids derived from petroleum by oxidation, tallow fatty acids, mixtures of the above acids, and dimers thereof. The term aliphatic monocarboxylic acid, as used henceforth, is intended to include all of the above acids.

In the course of the amidation some simultaneous esterification may occur. The amount of esterification which occurs relative to amidation depends upon a number of factors such as the time and temperature of reaction and the mole ratios of fatty acid to glucamine. In general, higher temperatures and prolonged reaction times favor amidation. Presence of excess acid, of course, favors esterification. Formation of ester-amides, as distinguished from amides, however, does not interfere with the utilization of these compounds as fuel additives.

Of considerable importance in the synthesis of compounds of this first type is the maintenance of a proper ratio between hydrophilic and hydrophobic (or lipophilic) constituents. As is well known in the art, hydroxyl groups such as are present in a polyol residue give molecules hydrophilic characteristics whereas alkyl and fatty acid residues contribute hydrophobic characteristics. Hydrophilic characteristics can also be added by condensation with alkylene oxides or mixtures thereof. In order to maintain a proper hydrophile-hydrophobe balance in the compounds of the invention, it has been found desirable that the sum of the carbon atoms in the alkyl group which is attached to the nitrogen atom and the

carbon atoms derived from the fatty acid total at least 15. Thus, for example, when lauric acid is used for amidation, the alkyl group attached to the nitrogen atom must contain at least 3 carbon atoms.

Additives of the first type discussed above may be represented as amides having the following formulas or as esters of such amides:

and

wherein R is a monovalent organic residue of a hexane pentol or an anhydro hexane pentol; R''' is a divalent residue of a hexane pentol or an anhydro hexane pentol, with the proviso that each nitrogen-terminating valence bond originates directly from a different carbon atom, said carbon atoms being separated from each other by at least two other carbon atoms; R' is selected from the group consisting of hydrogen, C₁ to C₆ alkyl, cycloalkyl hydrocarbon radicals which contain at least 5 carbon atoms; and

is the acyl radical of an aliphatic monocarboxylic acid which contains from 12 to 26 carbon atoms per molecule; provided, however, that the carbon atoms in R' plus those in the acyl radical total at least 15.

Products responding to the above generic formulae also include the cyclized acylation products of glucamines (as distinguished from N-alkyl glucamines) which would give compounds having structures of which the following are representative.

As stated above, the second type of acylation products may be broadly characterized as esters of tertiary hexyl amines. Illustrative of these products are the following, which are derived from an N-alkyl glucamine and which may be referred to as mono fatty acid esters of "cyclized" N-methyl glucamine:

These compounds are made by first cyclizing an N-alkyl glucamine and thereafter reacting the product with a fatty acid at temperatures above about 180° C. The acids which may be used for esterification are the same as those which are suggested above for amidation of

the compounds of the first type and the same hydrophile-hydrophobe considerations also apply.

These products may also be made by reacting a primary amine such as glucamine for instance, with one mol of an alkylene oxide to form a secondary amine, such as for instance N-hydroxy ethyl glucamine. Such secondary amines may then be cyclized to form a tertiary amine and thereafter acylated to form an ester.

Alternatively a primary amine may be reacted with two mols of alkylene oxide to form a tertiary amine. Thereafter, the tertiary amine may be acylated to form an ester.

Examples of the preparation of some esters of tertiary hexyl amines are the following:

Example II-A

30 390 grams (2 mols) of N-methyl glucamine were heated, with stirring, under a nitrogen atmosphere at from 180°-196° C. for 7½ hours during which time 36½ cc. (2 mols) of H₂O were evolved. 176 grams of dark product were removed. To the balance (1 mol) of the product were added 282 grams (1 mol) of oleic acid. These reactants were heated together at 180°-208° C. for 3 hours, during which time 24½ cc. H₂O were evolved. The final product was an oleic acid ester of cyclized N-methyl glucamine.

Example II-B

30 N-methyl, N-hydroxy ethyl glucamine was prepared by condensing N-methyl glucamine and ethylene oxide in a 1:1 mol ratio and without catalyst. To 122 grams of this product were added 287 grams of oleic acid and the reaction continued for 2½ hours in a nitrogen atmosphere at temperatures ranging from 188° C. to 202° C. 35 During this period 28 cc. of aqueous distillate were collected. The final product had an acid number of 13.5, a saponification number of 142, a hydroxyl number of 243 and an HCl equivalent of 712.

Example II-C

40 40 To 120 grams of N-methyl, N-hydroxy ethyl glucamine were added 175 grams of tallow fatty acid and the reaction continued for 2 hours 50 minutes in a nitrogen atmosphere at temperatures ranging from 195-205° C. 45 During this period 23 cc. of aqueous distillate were collected. The final product had an acid number of 10.7, a saponification number of 114, a hydroxyl number of 305 and an HCl equivalent of 924.

45 Fuel formulations which embody the invention give satisfactory results in keeping with the above outlined desiderata. Among these are the following:

Example III

	Percent by weight
JP-4 jet fuel	99.975
55 Product of Example II-A	.025
	100.000

60 The above formulation has a resistivity of 1×10^{10} ohm-centimeters. When the fuel was continuously pumped through a closed loop no static build-up could be detected.

Example IV

	Percent by weight
65 JP-4 jet fuel	99.00
Product of Example I-A	1.00
	100.00

70 The above formulation had a resistivity of 2.9×10^8 ohm-centimeters. When the fuel was continuously pumped through a closed loop, no static build-up could be detected. To these formulations may be added usual amounts of corrosion inhibitor, anti-knock compounds and the like.

Other suitable formulations include the following:

Example V

	Percent by weight
JP-3 jet fuel	99.995
Lauric acid amide of N-pentyl glucamine	.005
	100.000

Example VI

Non-leaded automotive gasoline	99.5
Tallow fatty acid amide of N-ethyl glucamine	0.5
	100.0

Example VII

JP-4 jet fuel	99.95
Product of Example I-B	.05
	100.0

Example VIII

JP-3 jet fuel	99.0
Product of Example I-C	1.0
	100.0

Example IX

Non-leaded automotive gasoline	99.9
Product of Example I-D	0.1
	100.0

Example X

JP-4 jet fuel	99.99
Product of Example II-B	.01
	100.0

Example XI

Kerosene	99.995
Product of Example II-C	.005
	100.0

Example XII

Hexane	98.2
Linoleic acid amide of cyclized invertamine	0.8
	100.0

One of the important tests made on these and other hydrocarbon formulations was that of electrical resistivity. In each instance the desired value of resistivity, namely below about 1×10^{11} ohm-centimeters, was achieved when the amount of additive used was within the range of from .005 to 1.0 percent by weight.

Some data, which are representative of tests made with JP-4 jet fuel are tabulated below:

TABLE I

Additive	Wt. percent in JP-4 Fuel	Resistivity, ohm-cm.
Oleic Amide of N-Methyl Glucamine	0.005	9.0×10^{10}
	0.01	3.9×10^{10}
	0.025	1.4×10^{10}
	0.05	6.4×10^9
	0.1	3.2×10^9
	0.25	1.2×10^9
Dimer Linoleic Acid Amide of Anhydro-methyl Glucamine	0.5	6.0×10^8
	1.0	2.9×10^8
	0.2	1.3×10^{11}

Having described our invention, what is claimed is:

1. A fuel having a resistivity of less than about 1×10^{11} ohm-centimeters comprising a liquid hydrocarbon which forms an equilibrium explosive mixture with air at a temperature between -20° F. and 210° F., said hydrocarbon having a Reid vapor pressure from about 0.1 to about 15 pounds per square inch, and from 0.0005 to 2.0 weight percent of an anti-static additive selected from the group consisting of an amide of a C_{12} to C_{26} aliphatic monocarboxylic acid and a primary hydroxy

hexyl amine, an amide-ester of a C_{12} to C_{26} aliphatic monocarboxylic acid and a primary hydroxy hexyl amine, an amide of a C_{12} to C_{26} aliphatic monocarboxylic acid and a secondary hydroxy hexyl amine, an amide-ester of a C_{12} to C_{26} aliphatic monocarboxylic acid and a secondary hydroxy hexyl amine, and an ester of a C_{12} to C_{26} aliphatic monocarboxylic acid and a tertiary hydroxy hexyl amine.

2. The fuel composition of claim 1 in which the secondary hydroxy hexyl amine is a cyclized hexyl amine.

3. The fuel composition of claim 1 in which the secondary hydroxy hexyl amine is an anhydro hexyl amine.

4. The fuel composition of claim 1 in which the tertiary hydroxy hexyl amine is a cyclized hexyl amine.

5. The fuel composition of claim 1 in which the tertiary hydroxy hexyl amine is an anhydro hexyl amine.

6. The fuel of claim 1 wherein the hydroxy hexyl amine is derived from fructose.

7. The fuel of claim 1 wherein said hydroxy hexyl amine is derived from glucose.

8. The fuel of claim 1 wherein said hydroxy hexyl amine is derived from galactose.

9. The fuel of claim 1 wherein said hydroxy hexyl amine is derived from sorbose.

10. The fuel of claim 1 wherein said hydroxy hexyl amine is derived from invert sugar.

11. A fuel having a resistivity of less than about 1×10^{11} ohm-centimeters comprising liquid hydrocarbon which forms an equilibrium explosive mixture with air at a temperature between -20° F. and 210° F., said hydrocarbon having a Reid vapor pressure from about 0.1 to about 15 pounds per square inch and as an anti-static additive, from 0.005 to 1.0 weight percent of an acylation product selected from the group consisting of amides and esters, of a C_{12} to C_{26} aliphatic carboxylic acid and glucamine.

12. A fuel having a resistivity of less than about 1×10^{11} ohm-centimeters comprising liquid hydrocarbon which forms an equilibrium explosive mixture with air at a temperature between -20° F. and 210° F., said hydrocarbon having a Reid vapor pressure from about 0.1 to about 15 pounds per square inch and, as an anti-static additive, from 0.005 to 1.0 weight percent of an acylation product selected from the group consisting of amides and esters of a C_{12} to C_{26} aliphatic carboxylic acid and an N-alkyl glucamine wherein said alkyl group contains from 1 to 6 carbon atoms, and wherein further, the total of the carbon atoms in said alkyl group plus the carbon atoms in said acid is at least 15.

13. The fuel of claim 12 wherein said acid is oleic acid and said alkyl group is methyl.

14. A fuel having a resistivity of less than about 1×10^{11} ohm-centimeters comprising liquid hydrocarbon which forms an equilibrium explosive mixture with air at a temperature between -20° F. and 210° F., said hydrocarbon having a Reid vapor pressure from about 0.1 to about 15 pounds per square inch and, as an anti-static additive, from .005 to 1.0 weight percent of an acylation product selected from the group consisting of amides and esters of a C_{12} to C_{26} aliphatic carboxylic acid and an N-alkyl anhydro glucamine wherein said alkyl group contains from 1 to 6 carbon atoms and wherein further, the total of the carbon atoms in said alkyl group plus the carbon atoms in said acid is at least 15.

15. The fuel of claim 14 wherein said acid is oleic acid and said alkyl group is methyl.

16. A fuel having a resistivity of less than about 1×10^{11} ohm-centimeters comprising liquid hydrocarbon which forms an equilibrium explosive mixture with air at a temperature between -20° F. and 210° F., said hydrocarbon having a Reid vapor pressure from about 0.1 to about 15 pounds per square inch and, as an anti-static additive, from 0.005 to 2.0 weight percent of an acylation product selected from the group consisting of

amides and esters of a C₁₂ to C₂₆ aliphatic monocarboxylic acid and a primary hexyl amine; the amount of said additive being sufficient to impart said resistivity characteristics to said fuel.

17. The fuel composition of claim 16 in which said primary hexyl amine is a primary anhydro hexyl amine.

18. A fuel having a resistivity of less than about 1×10¹¹ ohm-centimeters comprising liquid hydrocarbon which forms an equilibrium explosive mixture with air at a temperature between -20° F. and 210° F., said hydrocarbon having a Reid vapor pressure from about 0.1 to about 15 pounds per square inch and, as an anti-static additive, from 0.005 to 2.0 weight percent of an acylation product selected from the group consisting of amides and esters of a C₁₂ to C₂₆ aliphatic monocarboxylic acid and a secondary N-alkyl hexyl amine wherein said alkyl group contains from 1 to 6 carbon atoms; the amount of said acylation additive being sufficient to impart said resistivity characteristics to said fuel.

19. A fuel having a resistivity of less than about 1×10¹¹ ohm-centimeters comprising liquid hydrocarbon which forms an equilibrium explosive mixture with air at a temperature between -20° F. and 210° F., said hydrocarbon having a Reid vapor pressure from about 0.1 to about 15 pounds per square inch and, as an anti-

static additive, from 0.005 to 2.0 weight percent of an acylation product selected from the group consisting of amides and esters of a C₁₂ to C₂₆ aliphatic monocarboxylic acid and a secondary N-alkyl anhydro hexyl amine wherein said alkyl group contains from 1 to 6 carbon atoms; the amount of said additive being sufficient to impart said resistivity characteristics to said fuel.
